UNITED STATES PATENT OFFICE.

ALEXANDER HARRISON BROWNLEY, OF ONEHUNGA, NEW ZEALAND.

DETACHABLE BUTTON.

SPECIFICATION forming part of Letters Patent No. 758,602, dated April 26, 1904.

Application filed March 19, 1903. Renewed March 22, 1904. Serial No. 199,428. (No model.)

To all whom it may concern:

Be it known that I, ALEXANDER HARRISON BROWNLEY, a subject of the King of Great Britain, and a resident of Onehunga, New Zealand, have invented a new and Improved Detachable Button, of which the following is a full, clear, and exact description.

My invention relates to detachable buttons—that is, to means for securing buttons so that the same may be readily removed from clothing.

While my invention admits of general use, it is of peculiar value to soldiers and sailors for use in connection with their uniforms.

I will describe a detachable button embodying my invention and then point out the novel features in the appended claims.

Reference is to be had to the accompanying drawings, forming a part of this specification, in which similar characters of reference indicate corresponding parts in all the figures.

Figure 1 is a sectional side elevation on the line 1 1 in Fig. 2 of a detachable button embodying my invention. Fig. 2 is an inverted plan or bottom view of the button. Fig. 3 is a sectional side elevation on the line 3 3 in Fig. 4; and Fig. 4 is an inverted plan somewhat similar to Fig. 2, but showing the disks in a different relative position.

30 The button-head 1 is provided with an eye 2 in the usual manner. A disk 3 is provided with a bearing 4, in which is journaled a hasp or swinging member 5, provided with a pivotal bearing 4². The hasp is provided with a head 6 and a neck 7. The disk 3 is provided with a slot 8 of suitable conformity to admit the head 6. Another disk 9, somewhat larger than the disk 3, is provided with a milled edge 10 and with a slot consisting of a wide portion 11 and a narrower portion 14, the slot having a general arc shape. The eyes 2 and the hasp 5 constitute the respective members of a two-part fastener.

45 A pin 12, provided with a head 13, secures the two disks together, while permitting of more or less relative movement between them. The disk 9 is provided with another arc-shaped slot 15, through which a curved tongue 16, integral with the disk 3, passes. The disk 9 is 50 provided with a small hole 17, and the disk 3

is provided with a raised annular bead 18, preferably made by stamping. The bead 18 is free to engage the hole 17 when the two disks are in the relative position indicated in Fig. 2. When, however, the two disks are 55 moved relatively to each other—as, for instance, when the milled head 10 is turned—the two disks spring slightly asunder, so that the bead 18 is free to glide from the hole 17 and to bind slightly against the disk 9, as indicated more particularly in Fig. 4.

It will be observed that the head 6 and curved tongue 16, passing through the slots 14 15, constitute a guide mechanism for maintaining the disks in a predetermined relation. 65

My invention is used as follows: The hasp 5 being opened, as indicated in Fig. 3, the eye 2 of the button-head 1 is inserted, and the hasp is moved into the position indicated in Fig. 1, the head 6 and neck 7 passing through the 70 slots 8 and 11. When this occurs, the disks are in the position indicated in Fig. 4. The milled edge 10 now being grasped by the fingers is turned radially, so as to occupy the position indicated in Fig. 2, whereupon the 75 bead 18 snaps into the hole 17, thus securing the two disks together tolerably firm. The head 6 is now in one end of the slot 14, as indicated, so that the hasp 5 cannot be moved. To take off the button, the milled head 10 is 80 rotated in the usual direction until the parts assume the position indicated in Fig. 4, and the hasp 5 being swung into the position indicated in Fig. 2 the eye 2 is then unhooked.

Having thus described my invention, I claim 85 as new and desire to secure by Letters Patent—

1. A detachable button, comprising a button-head provided with one member of a two-part fastener, a disk provided with another member of said fastener, said last-mentioned 90 member being free to swing relatively to said disk for the purpose of engaging and disengaging said first-mentioned fastening member, a second disk provided with a slot for engaging said swinging member, and means for connecting said disks together so as to permit relative movements between the same.

2. A detachable button, comprising a button-head provided with one member of a two-part fastener, a disk provided with the other 100

- member of said fastener, said last-mentioned member being free to swing relatively to said disk for the purpose of engaging and disengaging said first-mentioned fastening member, 5 a second disk provided with a slot for engaging said swinging member, means for connecting said disks together so as to permit relative movements between the same, and a guide mechanism for maintaining said disks in a predetermined relation notwithstanding said movements.
3. A detachable button, comprising a button-head provided with one member of a two-part fastener, a disk provided with the other 15 member of said fastener, said last-mentioned member being free to swing relatively to said disk for the purpose of engaging and disengaging said first-mentioned fastening member, a second disk provided with a slot for engaging said swinging member, means for connecting said disks together so as to permit relative movements between the same, and a locking device for normally maintaining said disks in a predetermined relative position.
- 20 4. A detachable button, comprising a button-head provided with one member of a two-part fastener, a disk provided with the other member of said fastener, said last-mentioned member being free to swing relatively to said disk for the purpose of engaging and disengaging said first-mentioned fastening member, a second disk provided with a slot for engaging said swinging member, means for connecting said disks together so as to permit relative movements between the same, guide mechanism for maintaining said disks in a predetermined relation notwithstanding said movements, and a locking device for normally maintaining said disks in a predetermined relative 25 position.
- 30 5. A detachable button, comprising a button-head provided with an eye, a disk provided with a hasp pivotally mounted thereon for the purpose of detachably engaging said eye, and also provided with a slot for engaging said hasp, a second disk journaled upon said first-mentioned disk and provided with an arc-shaped slot for temporarily securing said hasp when said disks are moved into certain positions relatively to each other, and a fasten-

ing device for normally securing said disks together in one of said predetermined relative positions.

6. A detachable button, comprising a button-head provided with an eye, a disk provided with a slot, a hasp pivotally mounted upon said disk and provided with a head and neck capable of passing through said slot, and a member revolubly connected with said disk and provided with a slot having wide and narrow portions, said wide portion being free to admit said head and said narrow portion being too narrow to admit the head. 55

7. A detachable button, comprising a button-head provided with an eye, a disk provided with a head, a hasp pivotally mounted upon said disk and provided with a head and neck capable of passing through said slot, a member revolubly connected with said disk and provided with a slot, having wide and narrow portions, said wide portion being free to admit said head and said narrow portion being too narrow to admit the head, and a fastening device for normally securing said disks together in a predetermined relative position. 65

8. A detachable button, comprising a button-head provided with an eye, a disk provided with a slot, a hasp pivotally mounted upon said disk and provided with a head and neck capable of passing through said slot, a revoluble member connected with said disk and provided with a slot having wide and narrow portions, said wide portion being free to admit said head and said narrow portion being too narrow to admit the head, a fastening device for normally securing said disks together in a predetermined relative position, said revoluble member being provided with a milled edge to facilitate its movements relatively to said disk, and guiding mechanism for maintaining said disk and said revoluble member in a predetermined working relation. 80

In testimony whereof I have signed my name to this specification in the presence of two subscribing witnesses.

ALEXANDER HARRISON BROWNLEY.
